STACK COVER MECHANISM

John W. Boswell and Horace W. Waters,
Macon, Ga.

Application March 19, 1947, Serial No. 735,746

8 Claims. (Cl. 105—62)

1

This invention relates to a stack cover mechanism and more particularly to a cover mechanism for simultaneously covering or uncovering a plurality of exhaust stacks.

The present invention is particularly applicable for use with Diesel type locomotives to prevent moisture from entering the exhaust stacks when the Diesel engines are shut down. As is well known, in the conventional type of Diesel locomotive, the exhaust stacks extend vertically upward from the roof of the locomotive and are open to the atmosphere. Accordingly, if the Diesel engines are shut down and the locomotive left in the open, it is readily possible for moisture to enter through the exhaust stacks and seriously damage the cylinders and valves in the engines.

Heretofore, it has been the usual practice to apply the exhaust stack covers by carrying them up on top of the locomotive and manually placing them over each stack. This is a relatively time-consuming procedure, and in freezing weather, can be a rather hazardous operation since the roof of a locomotive is oval and becomes quite slippery if coated with ice.

To overcome these disadvantages, we have invented a stack cover mechanism which is carried on the locomotive and which can be operated from within the locomotive cab. By a simple manipulation of a control handle, the locomotive exhaust stacks can be simultaneously covered or uncovered. Our mechanism is rugged and reliable in service and enables the person operating the locomotive to know, before he leaves the locomotive cab, whether the exhaust stacks are covered or uncovered. There is no need to climb up onto the top of the locomotive to apply or remove the stack covers.

It is, therefore, an object of our invention to provide a rugged and reliable stack cover mechanism particularly adapted for use on locomotives to simultaneously cover or uncover the exhaust stacks.

It is another object of our invention to provide a stack cover mechanism particularly adapted for use on locomotives in which individual stack covers are attached to an actuating means common to each of them which is operated from within the cab of the locomotive thereby eliminating the necessity of climbing up on the locomotive to apply or remove the covers by hand.

It is still another object of our invention to provide a stack cover mechanism particularly adapted for use on locomotives which enables the operator of the locomotive to cover or uncover the locomotive exhaust stacks from within the locomotive cab and to know, before he leaves

2

the locomotive cab, whether the exhaust stacks are covered or uncovered.

It is a further object of our invention to provide a stack cover mechanism particularly adapted for use on locomotives in which individual stack covers are attached to an actuating shaft common to each of them which enters into and is operated from within the cab of the locomotive and in which means is provided to prevent the entrance of moisture where the shaft enters the locomotive cab.

It is a still further object of our invention to provide a stack cover mechanism particularly adapted for use on locomotives in which individual stack covers are attached to an actuating shaft which includes flexible connections and in which guide means are provided to prevent binding of the shaft during operation.

These and other objects and advantages of our invention will become apparent from the following description taken in conjunction with the attached drawings in which:

Figure 1 is a side elevation view showing a Diesel type locomotive with one form of our stack cover mechanism mounted thereon, said mechanism being shown in stack closed position;

Figure 2 is a plan view of the stack cover mechanism shown in Figure 1 and also shows a portion of the roof of the locomotive;

Figure 3 is an enlarged cross-sectional view taken on line III—III of Figure 2 but with the stack cover being shown in open position instead of closed position as is shown in Figure 2;

Figure 4 is an enlarged end view of the stack cover mechanism shown in Figures 1 and 2, as viewed from the handle end of the mechanism;

Figure 5 is an enlarged detail view showing the manner in which the stack cover mechanism extends into the locomotive cab;

Figure 6 is a cross-sectional view, taken on lines VI—VI of Figure 5, showing the seal arrangement;

Figure 7 is a side elevation view showing the upper portion of a locomotive similar to that shown in Figure 1, with an alternate form of our stack cover mechanism mounted thereon, said cover mechanism being shown in stack closed position;

Figure 8 is a plan view of the stack cover mechanism shown in Figure 7 and also shows a portion of the roof of the locomotive shown in Figure 7;

Figure 9 is a view similar to that of Figure 7 with the stack cover mechanism being shown in stack open position;

Figure 10 is an enlarged plan view of the loco-

motive stack cover shown at the right-hand end of Figure 8, but with said stack cover being shown in stack open position; and

Figure 11 is a cross-sectional view taken on line XI—XI of Figure 10.

Figure 12 is a vertical cross-sectional view taken on line XII—XII of Figure 3.

While we have illustrated practical embodiments of our invention as being particularly applicable to locomotive vehicles, it is to be realized that our invention is also applicable to other types of power plants having an exhaust stack and control cab arrangement with which our stack cover mechanism could be readily used. Accordingly, we do not intend, by our specific reference to locomotive vehicles, to restrict the scope of our invention solely to such vehicles.

In Figure 1 of the drawings, the roof of the Diesel type locomotive 10 is indicated generally by the reference numeral 11 and the locomotive cab is indicated generally by the reference numeral 12. Mounted upon the locomotive roof 11 are a plurality of individual brackets 13 which are positioned along a line extending lengthwise of the locomotive roof and to one side of the locomotive exhaust stacks 16, and which support sections of a longitudinal shaft indicated generally by the reference numeral 14. The longitudinal shaft 14 has attached thereto a plurality of stack covers 15, which, in Figures 1 and 2 of the drawings, are shown as covering the locomotive exhaust stacks 16.

This longitudinal shaft 14, which may be designated as a control shaft, is made up of a plurality of individual shaft sections 17. As can be seen from Figures 1 and 2, these individual shaft sections 17 extend longitudinally of the locomotive 10 and above the roof 11. Universal joints 18 interconnect the individual shaft sections 17 to provide a flexible articulated shaft arrangement. The brackets 13 receive the shaft sections to guide and maintain them in substantial alignment. For example, each shaft section 17 above the roof of the locomotive is supported, between the universal joints 18, by one or more of the brackets 13 to maintain that shaft section steady and in alignment relative to the locomotive exhaust stacks 16. Of course, adjacent shaft sections may not be exactly in alignment with each other because of the universal joint connection 18 between them. However, the universal joints 18 are provided to permit some variation in alignment between the adjacent shaft sections in order that the individual sections will not bind against their support brackets 13 during operation of the stack cover mechanism. It should be apparent that if a single continuous long shaft were provided along the roof of the locomotive, possible binding of this shaft might occur during usage of the mechanism and consequently, the articulated shaft arrangement provides the flexibility to guard against such a possibility. Furthermore, having separable shaft sections makes it possible to replace individual sections and stack covers more readily.

Each guide bracket 13 includes a horizontal flange 19 which is suitably secured, as by welding, to the locomotive roof 11. Each guide bracket also includes a substantially vertical body portion 20 having a hollow pipe 21 extended therethrough to form a journal. As can be seen from Figures 1 and 2 of the drawings, the hollow pipe 21 extends horizontally and equally from opposite sides of the body portion 20 of each bracket 13. This hollow pipe 21 thus forms a bearing which receives an individual shaft sec-

tion 17 and each of the hollow pipes 21 is of larger diameter than shaft section 17 carried by it so that the shaft section will not bind within the bearing member 21 and yet will be guided and supported by the bearing to prevent excess vibration or misalignment of the shaft section during operation of the locomotive.

The stack covers 15 are substantially flat metal members which are attached along one side to individual shaft sections 17. In the embodiment of our invention illustrated in Figures 1 and 2, each stack cover 15 is shown as being of sufficient length to cover a pair of exhaust stacks 16. While this is a preferable arrangement, it by no means excludes the possibility of having an individual separate cover for each locomotive exhaust stack. Referring to Figures 2 and 3, the stack covers 15 are shown as being welded along an edge 22 thereof to a shaft section 17. This, of course, rigidly connects the stack covers to the shaft sections so that, upon movement of the shaft sections, the stack covers will also be moved. While welding is employed by us as the means of attachment between the stack covers and the shaft sections, it is readily evident that suitable bracket attachments or rivet attachments could be used. Again referring to Figures 1 and 2, it can be seen that the individual stack covers are aligned longitudinally and are all attached along the same sideline to the control shaft 14 so that, upon movement of this shaft, all of the covers will move simultaneously.

At one end of the control shaft 14, a shaft section 17 extends into the locomotive cab 12. Details of this arrangement are best obtained from Figure 5 of the drawings. There it can be seen that a hollow tube 23 extends at an angle to the horizontal through the roof 24 of the locomotive cab 12. A weld connection is made between the hollow tube 23 and the locomotive cab roof 24 as is indicated at 25 to exclude moisture from entering the cab where the tube enters the cab and to rigidly support this tube. The end shaft section 17 passes through this hollow tube and terminates at a handle 26 which is positioned within the locomotive cab 12. A suitable socket connection 27 can be made between the handle and the end of the shaft section 17. Where the shaft section 17 enters the tube 23, a cap 27 is provided which contains an annular seal 28 for preventing moisture from entering the locomotive cab through the tube 23. Details of this arrangement can be observed from Figure 6 of the drawings. Preferably, the cap 27 is screwed onto the tube 23 and retains the seal 28 firmly in place.

While the seal 28 prevents the passage of moisture into the tube 23, it is not so tight as to prevent free movement of the shaft section 17.

At its end opposite the handle 26, the shaft section 17 is secured to a bifurcated member 29 which coacts with a similar bifurcated member 30 attached to the adjacent shaft section 17 to form a universal joint 18. Of course, this type of universal joint is well known and forms, per se, no part of the present invention. By means of this type of universal connection the shaft sections can be simultaneously rotated even though they are not in longitudinal alignment.

In Figure 4 of the drawings, the handle 26 is shown in solid outline as being in "handle closed" position. In this position of the handle, the stack covers 15 are likewise closed, as can be seen from Figure 4. The stack covers, of course, rest upon the exhaust stacks 16 in closed position. To open the exhaust stacks, the handle 26 is rotated substantially 180° as is indicated in dotted

outline in Figure 4. When this occurs, the stack covers 15 likewise are rotated substantially 180°, also indicated in dotted outline in Figure 4 and come to rest upon support brackets 31 which are positioned in longitudinal alignment along the roof 11 of the locomotive adjacent the exhaust stacks 16 and to one side of the control shaft 14. There is a support bracket 31 for each of the stack covers 15.

Each of these support brackets consists of a metal member having a body portion 32 in the form of an inverted V and oppositely extending foot flanges 33 and 34. The foot flanges are secured, as by welding, to the roof 11 of the locomotive and the body portion 32 is of substantially the same height as an exhaust stack 16. The support brackets 31 are positioned with their foot portions 33 and 34 extending along a common line substantially parallel to the control shaft 14 and, being of substantially the same height as the exhaust stacks 16, provide a support which will allow the stack covers 15 to rest substantially horizontal upon the brackets when in open position.

In the embodiment of our invention illustrated in Figures 7-11 of the drawings, the stack cover mechanism is slidable between open and closed positions. Referring to these figures, 35 denotes the upper portion of a locomotive similar to the locomotive 10 shown in Figure 1 of the drawings. This locomotive 35 includes a control cab 36 and has a roof designated generally by the reference numeral 37. A plurality of exhaust stacks 38 project upward from the roof 37 and, of course, these exhaust stacks are aligned lengthwise of the locomotive.

A plurality of exhaust stack covers 39 are in longitudinal alignment and, in the arrangement disclosed in Figures 7-11 inclusive, one exhaust stack cover is provided for each pair of exhaust stacks 38 similarly to the provision of a stack cover 15 for each pair of exhaust stacks 16 previously described. Naturally, single separate covers could be provided for each exhaust stack if so desired. These exhaust stack covers 39 are substantially flat metal members, and each includes a pair of openings 40 and 41, each of these openings being substantially equal in area to the area of each exhaust stack opening 70. As can be observed from Figures 8 and 10, the openings 40 and 41 are off-center lengthwise of the stack cover 39 so that there is a cover area 42 to one side of opening 40 and another cover area 43 between opening 40 and opening 41. These cover areas 42 and 43 are sufficient to cover the exhaust stack openings 70 of a pair of adjacent exhaust stacks 38 when the stack cover 39 is positioned so that the opening 40 is between the exhaust stack openings. This latter positioning is illustrated in Figure 8 of the drawings and it can be seen that each exhaust stack 38 is effectively covered by the stack covers 39.

The stack covers 39 are interconnected by members 44, 45 and 46 which may be either metal rods or pipes. Referring to Figure 8, these connecting members are positioned to extend from the end of one stack cover to the end of the next stack cover along a center line drawn lengthwise of these stack covers. The connection between an edge of a stack cover 39 and its connecting member such as the members 44-46 inclusive, may be made by welding or riveting or some such equivalent means.

A shaft member 47 is connected to and extends from the stack cover 39 nearest the locomotive

5 cab 36 to a universal joint connection 48. A coupling link 50 extends between the universal joint 48 and a second universal joint 49. From this latter universal joint a shaft member 51 extends through a tube or pipe 52 into the interior of the locomotive cab 36. The hollow pipe 52 extends through the roof of the locomotive cab at an angle thereto and is rigidly welded in position. The pipe 52 also has a seal construction 53 for preventing moisture from entering the locomotive cab through the hollow pipe. This arrangement of the hollow pipe 52 including the seal 53, is similar to the construction previously described with reference to Figures 5 and 6 of the drawings.

10 A control handle 54 is attached to an end of shaft member 51 and this handle 54 is, of course, positioned on the inside of the locomotive cab 36. Since the stack covers 39 are interconnected 15 by the connecting rods 44-46, to form a rigid assembly, and since the shaft member 47 connects this assembly to the connecting link 50, which is, in turn connected to the shaft member 51, all of these members make a unitary mechanism which can be actuated from within the locomotive cab 36 by pulling or pushing upon the handle 54.

15 Each pair of adjacent exhaust stacks 38 is provided with a pair of stack cover guides 55 and 56. Details of the cover guide arrangement are best obtained from Figures 10 and 11. As viewed there, it can be seen that guide 55 includes a flange 57, which is welded or riveted to the exhaust stacks, and an additional flange portion 58 which is reversely bent to form a guide groove 59. Similarly, the cover guide 56 includes a flange 60, which is welded or riveted to the exhaust stacks, and an additional flanged portion 61 which is reversely bent as indicated to form a guide groove 62 facing the guide groove 59. By means of these stack cover guides 55 and 56, the stack covers 39 are maintained in proper alignment and against sideways shifting since the grooves, such as grooves 59 and 62 of the guide members, guide the edges such as edges 63 and 64 of the stack covers. In addition, the shaft member 47 passes through and is supported by a guide bracket 65 and the connecting member 45 passes through and is supported by a guide bracket 66. The guide brackets 65 and 66 are constructed and function in similar manner to the guide brackets 13 previously described.

20 From the present description, it can be seen that when the control handle 54 is pushed until it abuts against the end 67 of hollow pipe 52 the individual stack covers 39 will have been pushed to the right as viewed in Figures 7-9, so that the openings 40 and 41 in each of these stack covers are out of alignment with the exhaust stack openings 70. Instead, the cover areas 42 and 43 are over these exhaust stack openings and hence the openings are closed against the entrance of moisture. When the control handle 54 is moved to the left as viewed in Figures 7-9, 25 the stack covers 39 are also moved to the left to bring the openings 40 and 41 of the stack covers 39 into alignment with the exhaust stack openings 70, thereby uncovering said openings. The amount by which the control handle 54 is moved depends, of course, upon the diameter of these various openings. As an aid, however, to enable the operator to know when the exhaust stacks are fully uncovered, the end stack cover 39, that is the stack cover farthest to the right in Figures 7-9, can be provided with stops 68

and 69 which engage the cover guides 55 and 56 when the exhaust stacks 38 are fully uncovered. Of course, the distance through which the stack covers have to move to cover the exhaust stacks can be gauged by having the control handle 54 abut against the end 67 of hollow pipe 52 when the stack covers have traveled the proper distance.

The universal joints 48 and 49 and the connecting link 50 therebetween are provided to prevent the shaft member 51 from exerting, during operation of the mechanism, undue strain on the hollow pipe 52 which extends into the locomotive cab 36. This flexible connection is sufficient to allow the shaft member 51 to travel substantially parallel to the axis of the hollow pipe 52 and yet impart a longitudinal thrust upon the shaft member 47. The universal joints 48 and 49 are generally similar to the universal joints 18 described with reference to the modification of Figures 1-6 of the drawings.

The component parts of our mechanism are chosen for simplicity and ruggedness to withstand hard usage and vibration encountered in heavy industrial use such as would be found in locomotive applications. The stack covers such as the stack covers 15 or 39 can be made of boiler plate material; the shaft sections, such as sections 17 and 47 and the connecting members 44-46 can be made of standard pipe or rod construction; and the guide brackets such as 13 and 65 and 66 can be made of bar steel. Connections of the various parts to the locomotive and to each other can be accomplished by welding to provide a rigid and strong construction which will withstand heavy usage.

With our mechanism it is readily possible for the operator of the locomotive to know, before he leaves the control cab, whether the exhaust stacks are covered or uncovered. If the rotatable type of mechanism, illustrated in Figures 1-6 of the drawings, is being used, the operator can readily tell whether the exhaust stacks are covered or not by simply observing the position of the control handle 26. If this handle is to the right as viewed in Figure 4 of the drawings, the exhaust stacks are covered. Conversely, if it is to the left, as viewed in this same figure, the stacks are uncovered. Similarly, if the embodiment of our invention illustrated in Figures 7-11, is being used, the operator can tell whether the exhaust stacks are covered by observing whether the control handle 54 is abutted against the end 67 of hollow pipe 52. Hence, for both embodiments of our invention which we have disclosed, it is readily possible to observe the positioning of the exhaust stack covers. As previously stated, this makes it unnecessary to climb up on top of the locomotive to check on the positioning of these covers or to apply or remove them.

While our mechanism is particularly adapted for use with a locomotive and we have so described it, it is also suitable for use with a power plant construction having at least one exhaust stack extending therefrom and a control cab or control location adjacent thereto from which the power plant is operated. When we say the control cab, we of course intend to cover any control location having a function similar to that of a control cab for a locomotive.

Also, we use the term "control shaft" to designate both the complete shaft assembly and also specific parts of this assembly. For example, referring to the modification illustrated in Figures 1-6 of the drawings, we use the term "control

shaft" broadly to refer to the entire shaft assembly 14. For this modification, we use the term more specifically to refer to the shaft section 17 which extends through the hollow tube 23 into the locomotive cab 12 and also to refer to the assemblage of shaft sections which extend along and above the roof of the locomotive. Hence, for this more specific use of the term "control shaft," the stack cover mechanism includes two control shafts, the one being made up of the shaft sections which are above the locomotive roof and the other being the shaft section which extends into the locomotive cab. Similarly, with respect to the modification of our invention illustrated in Figures 7-11 of the drawings, we use the term "control shaft" to refer broadly to the complete assemblage of connecting rods 44-46, shaft 47, connecting link 50, and shaft 51. We also use the term specifically to refer to the assemblage above the roof of the locomotive, this being the connecting rods 44-46 and shaft 47, and to refer to the shaft section 51 which extends into the locomotive cab 36. Hence, for the more specific use of the term "control shaft" for this modification, the mechanism contains two shafts, the one being made up of sections positioned above the locomotive roof and the other being the shaft section 51 which extends into the locomotive cab 36. We mention this usage of the term "control shaft" merely to clarify the language of the claims. By the term "control cab" we refer to any convenient position within the cab or engine room of the locomotive.

Therefore, while we have illustrated and described particular embodiments of our invention, we wish it to be understood that we do not wish to be restricted solely thereto, but that we do intend to cover all modifications thereof which would be apparent to one skilled in the art and which come within the spirit and scope of our invention.

We claim as our invention:

1. The combination with a vehicle including a control cab and a power plant having a plurality of exhaust stacks extending therefrom, of a stack cover mechanism comprising a plurality of stack covers slidable between two positions, in one of which the exhaust stacks are covered and in the other of which the exhaust stacks are uncovered, a slidable control shaft, means connecting each of said stack covers to said slidable control shaft for movement therewith, and means to slide said control shaft from within the control cab.

2. The combination with a locomotive having a plurality of exhaust stacks, of a stack cover mechanism comprising a stack cover for each of said exhaust stacks, an articulated control shaft extending lengthwise of said locomotive, means rigidly connecting each of said stack covers to said articulated control shaft for swinging movement laterally of the locomotive about the axis of said shaft, guide brackets attached to the roof of said locomotive, said articulated control shaft being supported by said guide brackets, and means to rotate said articulated shaft from within the locomotive cab whereby the stack covers are simultaneously moved to either cover or uncover said exhaust stacks.

3. The combination with a locomotive having a plurality of aligned exhaust stacks, of a stack cover mechanism comprising a stack cover for each of said stacks, said stack covers being movable between two positions, in one of which the exhaust stacks are covered and in the other of

which the exhaust stacks are uncovered, a control shaft extending lengthwise of said locomotive, said control shaft having a plurality of sections interconnected by universal joints, means rigidly connecting said stack covers to sections of said control shaft for swinging movement laterally of the locomotive about the axis of said shaft, means attached to the roof of said locomotive for supporting the sections of said control shaft, means to rotate said control shaft from within the locomotive cab, and means attached to the roof of said locomotive for supporting said stack covers when the latter are in stack uncovered position.

4. The combination with a locomotive having a plurality of exhaust stacks, of a stack cover mechanism comprising a stack cover for each of said exhaust stacks, shaft members rigidly interconnecting said stack covers, said shaft members being positioned to extend lengthwise of said locomotive, and one of said shaft members extending into the locomotive cab, a control handle attached to said last mentioned shaft member for sliding the shaft members and stack covers between two positions, in one of which the exhaust stacks are covered and in the other of which the exhaust stacks are uncovered, and means attached to the locomotive exhaust stacks for guiding the stack covers during movement thereof.

5. A stack cover mechanism for covering and uncovering the stacks of a locomotive or the like comprising a plurality of substantially flat stack covers, a control shaft having a plurality of sections extending longitudinally of the locomotive, means rigidly connecting said stack covers edge-wise to sections of said control shaft for swinging movement about the axis of said shaft as said shaft is rotated, a flexible connection between one of said shaft sections and another of said shaft sections, and a handle mechanism attached to one of said flexibly connected shaft sections for actuating said shaft sections and said stack covers simultaneously.

6. A stack cover mechanism for covering and uncovering the stacks of a locomotive or the like comprising a plurality of aligned stack covers movable between a position covering the

openings and a position uncovering the openings, a plurality of connecting members rigidly interconnecting said stack covers to form a rigid assembly of alternate connecting members and stack covers.

7. A stack cover mechanism comprising a plurality of substantially flat aligned stack covers, a control shaft having sections connected at each end thereof to said stack covers to form a rigid assembly of alternate stack covers and shaft sections, a flexible connection between an end shaft section and its adjacent shaft section, and a control handle attached to said end shaft section for slidably moving said shaft sections and stack covers simultaneously.

8. A stack cover mechanism for a vehicle having a plurality of aligned stack openings in the roof thereof comprising a control rod, a plurality of cover members rigidly secured to said control rod for positive movement thereby toward or away from the stack openings, each of said cover members being movable from a position completely closing the associated stack to a position completely opening said stack and a tubular guide member passing through an opening in the roof of the vehicle with a weather-tight seal at the opening, said control rod being formed in sections with a first section journaled in said tubular member and extending into the cab of the vehicle and a second section carrying said cover members and universally connected to said first section.
